ELECTRIC-MOTOR DRIVE.

1,089,783.

Specification of Letters Patent.

Patented Mar. 10, 1914.

Application filed August 29, 1913. Serial No. 787,276.

To all whom it may concern:

Be it known that I, KARL A. PAULY, a citizen of the United States, residing at Schenectady, county of Schenectady, State 5 of New York, have invented certain new and useful Improvements in Electric-Motor Drives, of which the following is a specification.

My invention relates to electric motor 10 drives and is particularly applicable to such drives for machines, driven by a plurality of motors which must be reversed, as for instance, universal reversing rolling mills.

A universal rolling mill is one in which 15 a piece of steel can be rolled simultaneously on all four sides, the mill being equipped with both horizontal and vertical rolls. The speeds of the rolls of such a mill depend upon the reductions produced in the piece 20 of steel in the two sets of rolls and the direction in which it is passing, that is, whether it is passing through the horizontal rolls first and then through the vertical rolls, or vice versa. If the reductions, and therefore, 25 the speeds of the horizontal and vertical rolls could be adjusted for a pass and these maintained continuously, each of the rolls might be driven by a motor, the speed of each of which being adjusted once and for 30 all. Since, however, a mill of this kind is required for a great variety of products, the relative speeds of the rolls are required to vary, and furthermore, the speeds of the rolls must be controlled so that the pieces of 35 steel will not buckle or stretch between the rolls.

To this end, my invention has for its object a novel electric motor drive for such a mill, or for any machine driven by a plurality 40 of motors, which must be reversed.

In accordance with my invention, I provide the machine with a plurality of motors, the speed of one of which is arranged to depend upon the load thereon, and cause 45 the motors to have different relative speeds when their direction of rotation is reversed.

Other features of novelty which characterize my invention are pointed out with particularity in the claims annexed to and 50 forming a part of this specification.

For a better understanding of my invention reference may be had to the following description taken in connection with the accompanying drawing in which the single 55 figure shows diagrammatically a universal

rolling mill provided with an electric motor drive in accordance with my invention.

In the drawing, 1 are horizontal rolls driven by a motor 2, and 3 are vertical rolls driven by a motor 4. The armatures of these 60 motors are supplied with current from any suitable source, as for example, a fly-wheel motor generator set 5 as shown. The field windings of these motors may be supplied from the same source as are the armatures, 65 or any other suitable source. I have shown a motor generator set 6 supplying these field windings.

If a piece of steel 7 enters the horizontal rolls 1 first, then the speed of the vertical rolls 3 must be higher than that of the horizontal rolls, while if the steel enters the vertical rolls first then the speed of the vertical rolls must be lower than that of the horizontal rolls. Since the maximum reduction 75 usually takes place in the horizontal rolls, the difference in speeds of the horizontal and vertical rolls is usually comparatively slight in the first case, but is usually considerable in the second case. If the steel enters the horizontal rolls first, the motors 2 and 4 revolve in one direction, while if the steel enters the vertical rolls first the motors 2 and 4 revolve in the opposite direction. This reversal of the motors is taken care 80 of by suitable means, as by a reversing or control switch 8 having stationary and movable contacts. In order that the rolls will have the relative speeds referred to above, I cause the motors to have different relative 85 speeds when their direction of rotation is reversed, preferably by changing the field strength of one of the motors, as by cutting a resistance into the circuit of its field winding. I also provide one of the motors with 90 means for causing its speed to depend upon its load, preferably causing it to slow down as the load thereon increases. I may accomplish this by means of a field winding supplied with current proportional to the armature current and connected accumulatively 95 with respect to the main field winding on the motor. With the motor driving the vertical rolls provided with such means, its speed will drop to the normal value assuming that the vertical rolls are taking a draft which calls for full load torque. If the draft is less than that which would call for full load on this motor, the tendency of this 100 motor will be to run at a speed greater than 105

110

that required and will assist the motor driving the horizontal rolls, the speed of the vertical rolls adjusting itself to that corresponding to full load torque. If the draft 5 of the vertical rolls is such as to require a torque in excess of full load torque on the motor 4 driving the vertical rolls, it will slow down beyond normal and the motor driving the horizontal rolls will assist the 10 motor driving the vertical rolls in forcing the steel between them. This transfer of the load from one motor to the other and consequent change of speed of the motor driving the vertical rolls will tend to prevent any buckling or stretching of the steel 15 between the rolls.

If, under certain conditions which might arise in certain universal rolling mills, there is danger of the vertical rolling mill motor having such an excessive torque as to stretch or buckle the material, this tendency can be reduced to harmless proportions by providing the motor 2 driving the horizontal rolls with means for causing its speed to depend 20 upon the load on motor 4 driving the vertical rolls, that is, causing the motor 2 to speed up when the load on motor 4 increases. I prefer to accomplish this by means of a field winding on the horizontal rolls motor supplied with current proportional to the armature current of the motor driving the vertical rolls and connected differentially with 25 respect to the main field winding of the motor driving the horizontal rolls.

Referring to the drawing more in detail, the fly-wheel motor generator set consists of a separately excited generator 9, a fly-wheel 10 and induction motor 11. The induction motor is supplied with alternating current 30 from mains 12. An automatic rheostat or slip regulator 13 is arranged to cut resistance into or out of the rotor circuit of the motor 11, and consists of a slip regulating or "torque" motor 14 connected in series with 35 the motor 11 and of a water rheostat 15, the plates of which are separated or brought together by the slight motion of the motor 14.

The exciter motor generator set 6 comprises an induction motor 16 driving a shunt 40 wound exciter 17 and a series exciter 18. The shunt wound exciter 17 supplies current to the mains 19 to which are connected the field windings 20 and 21 of motors 2 and 4, through adjusting rheostats 22 and 23. The 45 field winding of generator 9 is also connected to the mains 19 through the reversing switch 8 and an adjusting rheostat 24.

The armatures of motors 2 and 4 are connected in parallel with the armature of generator 9. The field winding of exciter 18 is connected in series with the armature of motor 4 so that the voltage generated by this exciter is directly proportional to the current flowing through the armature of motor 4, 55 and consequently the load thereon. A field

winding 25, which is cumulatively connected with respect to field winding 21, is connected to the armature of exciter 18 through the reversing switch 8 and an adjusting rheostat 26. Under certain conditions as explained above it may be deemed desirable to supply motor 2 with a field winding 27 connected differentially with respect to field winding 20. This winding 27 and an adjusting rheostat 28 are shown as connected in parallel with winding 25 and rheostat 26. 70 75

Since the voltage of exciter 18 is proportional to the load on motor 4, and since winding 25 on this motor is connected to the brushes of this exciter so as to be cumulative with respect to winding 21, motor 4 slows down upon an increase in the load on this motor. Since, winding 27 of motor 2 is also connected to the brushes of exciter 18 and so as to be differential with respect to winding 20, the speed of motor 2 also depends upon the load on motor 4, but in such a way as to increase with the load on motor 4 instead of decreasing. 80 85

I have shown the control switch 8 with four positions forward and four reverse. When the control switch is in any of the forward positions 1', 2', 3' or 4', connections are made so that motors 2 and 4 turn the rolls 1 and 3 in such a direction that steel, 90 in order to be rolled, must enter the horizontal rolls first. When the control switch is in any of the reverse positions 1'', 2'', 3'' or 4'', the motors turn the rolls 1 and 3 in the opposite direction so that in order to roll the steel, it must enter the vertical rolls 95 first. The system of control employed is that known as the "Ward Leonard" system. The exciter 17 supplies excitation to the generator 9, the armature of which supplies current to the motors 2 and 4. In order to control the speed of these motors resistance sections 29 are inserted by the switch 8 in series with the field winding of generator 9, and in order to reverse these 100 motors the potential of generator 9 is reversed by reversing the connections of its field winding with the exciter 17 by the control switch 8. 105 110 115

As explained above, the field windings 20 and 21 of motors 2 and 4, respectively, are connected in parallel across the mains 19 supplied with current by exciter 17, and since motor 4 must drive the rolls 3 at a higher relative speed than the rolls 1 are 120 driven when steel enters the horizontal rolls 1 first, a resistance 30, which is preferably adjustable, is arranged to be cut into the circuit of field winding 21. This resistance 125 weakens the field of motor 4 when the switch 8 is in any of the forward positions, and thereby causes the motor 4 to revolve at a higher speed than motor 2. By making the rheostat 30 adjustable, the speed of motor 4 may be changed when the motors are run- 130

ning forward if desirable because of a difference in the size, section or characteristic of the steel to be rolled. But when the steel enters the vertical rolls first, motor 4 must run slower than motor 2, and I therefore provide the switch 8 with a pair of contacts 31 for short-circuiting the resistance 30 during all of the reverse positions.

Since the field of exciter 18 is in series with the armature of motor 4, and since the motors are reversed by reversing the direction of the current in their armatures, it is necessary to reverse the connections between the armature of exciter 18 and the field windings 25 and 27 when the motors 2 and 4 are reversed, in order that field winding 25 is always connected cumulatively with respect to field winding 21, whereby motor 4 slows down when the load thereon increases, and field winding 27 is always connected differentially with respect to field winding 20, whereby motor 2 speeds up when the load on motor 4 increases. The connections between the armature of exciter 18 and field windings 25 and 27 are reversed through the lower four contacts of reversing switch 8 in the well known manner.

Although I have described my invention in connection with a particular system of rolling mill drive, I desire it to be understood that it is not limited thereto, and may be used in any system of reversing motor drive, and I aim in the appended claims to cover all modifications which do not depart from the spirit and scope of my invention.

What I claim as new and desire to secure by Letters Patent of the United States, is:—

1. In combination, a plurality of motors, means for causing the speed of one of said motors to depend upon the load thereon, means for reversing said motors, and means for causing said motors to have different relative speeds when their direction of rotation is reversed.

2. In combination, a plurality of motors, means for causing one of said motors to slow down as the load thereon increases, means for reversing said motors, and means for causing said motors to have different relative speeds when their direction of rotation is reversed.

3. In combination, a plurality of motors, means for causing the speed of one of said motors to depend upon the load thereon, means for reversing said motors, and means for changing the field strength of one of said motors when its direction of rotation is reversed.

4. In combination, a plurality of motors, means for causing one of said motors to slow down as the load thereon increases, means for reversing said motors, and means for changing the field strength of one of said motors when its direction of rotation is reversed.

5. In combination, a plurality of motors, means for causing the speed of one of said motors to depend upon the load thereon, means for reversing said motors, a resistance, and means for cutting said resistance into the field circuit of one of said motors when its direction of rotation is reversed. 70

6. In combination, a plurality of motors, means for causing one of said motors to slow down as the load thereon increases, means for reversing said motors, a resistance, and means for cutting said resistance into the field circuit of one of said motors when its direction of rotation is reversed. 75

7. In combination, a plurality of motors, a separately excited generator supplying the armatures thereof, means for energizing the field windings of said motors and generator, means for varying the field strength of said generator so as to vary the speeds of said motors, means for causing the speed of one of said motors to depend upon the load thereon, means for reversing said motors, and means for causing said motors to have different relative speeds when their direction of rotation is reversed. 80 85 90

8. In combination, a plurality of motors, a separately excited generator supplying the armatures thereof, means for energizing the field windings of said motors and generator, means for varying the field strength of said generator so as to vary the speeds of said motors, means for causing one of said motors to slow down as the load thereon increases, means for reversing said motors, and means for causing said motors to have different relative speeds when their direction of rotation is reversed. 95 100

9. In combination, a plurality of motors, a separately excited generator supplying the armatures thereof, means for energizing the field windings of said motors and generator, means for varying the field strength of said generator so as to vary the speeds of said motors, means for causing the speed of one of said motors to depend upon the load thereon, means for reversing said motors, and means for changing the field strength of one of said motors when its direction of rotation is reversed. 105 110 115

10. In combination, a plurality of motors, a separately excited generator supplying the armatures thereof, means for energizing the field windings of said motors and generator, means for varying the field strength of said generator so as to vary the speeds of said motors, means for causing one of said motors to slow down as the load thereon increases, means for reversing said motors, and means for changing the field strength of one of said motors when its direction of rotation is reversed. 120 125

11. In combination, a plurality of motors, a separately excited generator supplying the armatures thereof, means for energizing the 130

- field windings of said motors and generator, means for varying the field strength of said generator so as to vary the speeds of said motors, means for causing the speed of one of said motors to depend upon the load thereon, means for reversing said motors, a resistance, and means for cutting said resistance into the field circuit of one of said motors when its direction of rotation is reversed.
12. In combination, a plurality of motors, a separately excited generator supplying the armatures thereof, means for energizing the field windings of said motors and generator, means for varying the field strength of said generator so as to vary the speeds of said motors, means for causing one of said motors to slow down as the load thereon increases, means for reversing said motors, a resistance, and means for cutting said resistance into the field circuit of one of said motors when its direction of rotation is reversed.
13. In combination, two motors, means for causing the speed of one of said motors to depend upon the load thereon, means for causing the speed of the other of said motors to depend upon the load on said first mentioned motor, means for reversing said motors, and means for causing said motors to have different relative speeds when their direction of rotation is reversed.
14. In combination, two motors, means for causing one of said motors to slow down as the load thereon increases, means for causing the other of said motors to speed up as the load on said first mentioned motor increases, means for reversing said motors, and means for causing said motors to have different relative speeds when their direction of rotation is reversed.
15. In combination, two motors, means for causing the speed of one of said motors to depend upon the load thereon, means for causing the speed of the other of said motors to depend upon the load on said first mentioned motor, means for reversing said motors, and means for changing the field strength of one of said motors when its direction of rotation is reversed.
16. In combination, two motors, means for causing the speed of one of said motors, to depend upon the load thereon, means for causing the speed of the other of said motors to depend upon the load on said first mentioned motor, means for reversing said motors, a resistance, and means for cutting said resistance into the field circuit of one of said motors when its direction of rotation is reversed.
17. In combination, two motors, means for causing one of said motors to slow down as the load thereon increases, means for causing the other of said motors to speed up as the load on said first mentioned motor in-
- creases, means for reversing said motors, and means for changing the field strength of one of said motors when its direction of rotation is reversed.
18. In combination, two motors, means for causing one of said motors to slow down as the load thereon increases, means for causing the other of said motors to speed up as the load on said first mentioned motor increases, means for reversing said motors, a resistance, and means for cutting said resistance into the field circuit of one of said motors when its direction of rotation is reversed.
19. In combination, two motors, a separately excited generator supplying the armatures thereof, means for energizing the field windings of said motors and generator, means for varying the field strength of said generator so as to vary the speeds of said motors, means for causing one of said motors to slow down as the load thereon increases, means for causing the other of said motors to speed up as the load on said first mentioned motor increases, means for reversing said motors, and means for causing said motors to have different relative speeds when their direction of rotation is reversed.
20. In combination, two motors, a separately excited generator supplying the armatures thereof, means for energizing the field windings of said motors and generator, means for varying the field strength of said generator so as to vary the speeds of said motors, means for causing one of said motors to slow down as the load thereon increases, means for causing the other of said motors to speed up as the load on said first mentioned motor increases, means for reversing said motors, and means for changing the field strength of one of said motors when its direction of rotation is reversed.
21. In combination, two motors, a separately excited generator supplying the armatures thereof, means for energizing the field windings of said motors and generator, means for varying the field strength of said generator so as to vary the speeds of said motors, means for causing one of said motors to slow down as the load thereon increases, means for causing the other of said motors to speed up as the load on said first mentioned motor increases, means for reversing said motors, a resistance, and means for cutting said resistance into the field circuit of one of said motors when its direction of rotation is reversed.
22. In combination, two motors, a separately excited generator supplying the armatures thereof, means for energizing the field windings of said motors and generator, means for varying the field strength of said generator so as to vary the speeds of said motors, means for causing one of said mo-

tors to slow down as the load thereon increases, means for causing the other of said motors to speed up as the load on said first mentioned motor increases, means for reversing said motors, an adjustable resistance, and means for cutting said resistance into the field circuit of one of said motors when its direction of rotation is reversed.

23. In combination, a plurality of motors, means for causing the speed of one of said motors to depend upon the load thereon, means for reversing said motors, an adjustable resistance, and means for cutting said resistance into the field circuit of one of said motors when its direction of rotation is reversed.

24. In combination, a plurality of motors, means for causing one of said motors to slow down as the load thereon increases, means for reversing said motors, an adjustable resistance, and means for cutting said resistance into the field circuit of one of said motors when its direction of rotation is reversed.

25. 25. In combination, a plurality of motors, a separately excited generator supplying the armatures thereof, means for energizing the field windings of said motors and generator, means for varying the field strength of said generator so as to vary the speeds of said motors, means for causing one of said motors to slow down as the load thereon increases, means for reversing said motors, an adjustable resistance, and means for cutting said resistance into the field circuit of one of said motors when its direction of rotation is reversed.

26. In combination, two motors, means for causing one of said motors to slow down as the load thereon increases, means for causing the other of said motors to speed up as the load on said first mentioned motor increases, means for reversing said motors, an adjustable resistance, and means for cutting said resistance into the field circuit of one of said motors when its direction of rotation is reversed.

27. In combination, a plurality of motors having main field windings, one of said motors having a second field winding connected accumulatively with respect to said main field winding and supplied with current proportional to the armature current thereof, means for reversing said motors, a resistance, and means for cutting said resistance into the main field circuit of one of said motors when its direction of rotation is reversed.

28. In combination, a plurality of motors having main field windings, one of said motors having a second field winding connected accumulatively with respect to said main field winding and supplied with current proportional to the armature current thereof,

means for reversing said motors, an adjustable resistance, and means for cutting said resistance into the main field circuit of one of said motors when its direction of rotation is reversed.

29. In combination, a plurality of motors having main field windings, one of said motors having a second field winding connected accumulatively with respect to said main field winding and supplied with current proportional to the armature current thereof, a resistance, a control switch for reversing said motors and for cutting said resistance into the main field circuit of one of said motors when its direction of rotation is reversed.

30. In combination, a plurality of motors having main field windings, one of said motors having a second field winding connected accumulatively with respect to said main field winding and supplied with current proportional to the armature current thereof, an adjustable resistance, a control switch for reversing said motors and for cutting said resistance into the main field circuit of one of said motors when its direction of rotation is reversed.

31. In combination, two motors having main field windings, one of said motors having a second field winding connected accumulatively with respect to its main field winding and supplied with current proportional to the armature current thereof, the other of said motors having a second field winding connected differentially with respect to its main field winding and supplied with current proportional to the armature current of said first mentioned motor, means for reversing said motors, a resistance, and means for cutting said resistance into the main field circuit of one of said motors when its direction of rotation is reversed.

32. In combination, two motors having main field windings, one of said motors having a second field winding connected accumulatively with respect to its main field winding and supplied with current proportional to the armature current thereof, the other of said motors having a second field winding connected differentially with respect to its main field winding and supplied with current proportional to the armature current of said first mentioned motor, means for reversing said motors, an adjustable resistance, and means for cutting said resistance into the main field circuit of one of said motors when its direction of rotation is reversed.

33. In combination, two motors having main field windings, one of said motors having a second field winding connected accumulatively with respect to its main field winding and supplied with current proportional to the armature current thereof, the

other of said motors having a second field winding connected differentially with respect to its main field winding and supplied with current proportional to the armature current of said first mentioned motor, a resistance, and a control switch for reversing said motors and for cutting said resistance into the main field circuit of one of said motors when its direction of rotation is reversed.

34. In combination, two motors, having main field windings, one of said motors having a second field winding connected accumulatively with respect to its main field winding and supplied with current proportional to the armature current thereof, the

other of said motors having a second field winding connected differentially with respect to its main field winding and supplied with current proportional to the armature current of said first mentioned motor, an adjustable resistance, and a control switch for reversing said motors and for cutting said resistance into the main field circuit of one of said motors when its direction of rotation is reversed.

In witness whereof, I have hereunto set my hand this 28th day of August 1913.

KARL A. PAULY.
